ABSTRACT OF THE DISCLOSURE

An integrated physical exercise device of the type utilizing a rope having terminals to be pulled against variable resistances, the device having an open frame structure within which is mounted shaft means about which multiple rope turns are wound, and pull resistance control means spaced outwardly from the shaft means to support an intermediate extent of the wound rope in a manner permitting variation of the number of rope turns and therefore the rope pull resistance.

BACKGROUND OF THE INVENTION

This invention aims to provide improvements in and departures from known physical exercise devices of the general type employing a rope having terminals for manual pull manipulations against frictional resistance to movement of an intermediate extent of the rope.

Heretofore, some exercise devices have imposed such resistance by wrapping multiple and variable turns of the rope about a shaft. Different expedients have been employed for variation of the number of wound turns of the rope, notably by rotation of a rope supporting and guide means relative to the shaft, or by arrangements otherwise requiring multiple relatively moving parts.

SUMMARY OF THE PRESENT INVENTION

A general object of the invention is to provide a unitary exercise device which is reduced to simple, practical and economical form possessing the full functional requirements desired in this type of exerciser, and having various advantages over the conventional devices by reason of greater simplicity in use and variable control, which result from its unique structure.

Generally contemplated is a unitized construction employing suspensile shaft means about which the intermediate rope extent is wrapped in multiple turns, and rope pull control means mounted in spaced and openly accessible relation with the shaft means so as to easily and visibly permit variation of the wrapped turns by replaceable looped support away from the shaft means. Being symmetrically located in relation to the rope turns, the control means assures equal pull resistance at the rope terminals.

In its more specific aspects the invention contemplates accommodation of the shaft and control means within an open frame structure which serves also to mount guides receiving the rope released from the shaft means and directing free extents of the rope convergently to relatively closely spaced release locations.

A preferred form of the invention employs a suspensile frame, bridged to junctures with its side extents by an essentially horizontal smooth surface shaft which receives the rope through frame-carried guides below the shaft. Top and bottom portions of the frame serve to mount the openly centered control means which may be in the form of simple hooks spaced above and below the shaft and about which the rope may be easily looped.

The invention will be more fully understood from the following description of an illustrative embodiment shown by the accompanying drawing in which:

2

BRIEF DESCRIPTION OF THE DRAWING

FIG. 1 is a view showing the exercise device in elevation;

FIG. 2 is a vertical section taken on broken line 2—2 of FIG. 1;

FIG. 3 is a transverse broken section on line 3—3 of FIG. 1; and

FIG. 4 is a view similar to intermediate FIG. 2 showing the shaft rope looped over the lower retaining means.

DESCRIPTION OF THE PREFERRED EMBODIMENTS

As shown in FIG. 1 the device comprises a strong rigid metal frame, generally indicated at 10, the upper sides 11 of which diverge downwardly at about 90° to the intermediate shaft supporting extents 12, below which the sides continue at 13 convergently to junctures with the bottom integral guide loops 14. The frame may be suspended, or supported in inverted position for upward rope pull, in any suitable manner as simply by a hook 15 inserted within the frame apex at 16 which is the top center of the frame symmetry below.

Rigidly bridging and joined at 17 to the frame side extents 12 is a somewhat larger diameter smooth surface shaft 18 which in the suspended or supported use condition of the device is essentially horizontal. The shaft length is such as to accommodate up to the number of rope turns that will provide maximum useable resistance to rope pull against the frictional resistance of the turns to pulled slippage about the shaft. Below that maximum resistance the rope turns and resistance may be progressively reduced to zero.

The rope 19, typically of woven nylon, has free terminal extents 20 with handles 21 from which the rope passes upwardly through guides 14 and upper guide loops 22 welded to the frame directly below the shaft 18. The intermediate rope extent between guides 22 may be given the desired number of turns on the shaft by grasping the rope opposite the shaft center and looping it one or more times about the shaft.

Provision is made for releasably retaining the rope extending between equal turns on the shaft, at locations 23 and 24 spaced respectively above and below the shaft and in alignment with the frame vertical axis. The rope support at 24 may be formed simply as a smoothly curved inner surface hook 25 depending from the frame bridge piece 26, and the support at 24 as a reversibly turned upstanding similar hook 27 welded to the frame between the guides 14. These supports serve as resistance control means for the rope pull in that by releasably retaining the rope, the latter may be given variable numbers of turns about the shaft and restored to either of the supports which thus accommodate the rope for increments of half turns. 55 When released from both supports the rope drops free of the shaft.

In use the exerciser is manipulated by pulling alternately the handled rope terminals against the equally balanced frictional resistances imposed by the turns about the shaft, as well as the resistance to pulling of the upwardly or downwardly convergent rope extents slideable against the inside surfaces of the hooks 25 or 27.

Of particular practical significance is the open exposure given the shaft and supports at 23 and 24 within the essentially coplanar frame, which permits clear observation of the rope condition on the shaft, as well as ready access to the supports for quick variation of the rope turns and pull resistances that may require changes to serve the purposes of prescribed exercise sequences.

It is to be understood that the drawing is illustrative of the invention in a typical though preferred form and that

various changes in details may be made without departure from the intended spirit and scope of the invention.

I claim:

1. An exercise device comprising an open frame having a top portion suspendable from a support and downwardly extending side portions, normally horizontal, straight shaft means within and having terminal portions engaged by said frame, a rope having successive turns wrapped about said shaft means and terminals for manual manipulation to pull the rope against the frictional resistance of its shaft means engagement, frame supported, hook-like, rope passing resistance control means operable to receive a distended looped extent of the rope intermediate shaft-wrapped turns and to permit variation of the number of the wrapped turns on said shaft means, and rope guide means carried by the frame and positioned below and spaced from the shaft means for passing terminal extents of the rope, said frame extending continuously about the shaft means to support said control means and said guide means in a common plane with said shaft means.

2. An exercise device according to claim 1, in which said resistance control means is positioned centrally of the number of rope turns on the shaft means and receives convergent extents of the rope.

3. An exercise device according to claim 1, in which said shaft means is a straight smooth surface shaft joined with said side portions of the frame.

4. An exercise device according to claim 3, in which said resistance control means is carried by the frame and is spaced outwardly and free from the wrapped longitudinal center of the shaft.

5. An exercise device according to claim 4, in which said control means is located both above and below the shaft.

6. An exercise device according to claim 3, including also a pair of upper guide means carried by the frame at spaced locations directing the rope extents passing from the shaft, and lower rope passing guide means carried by the frame at relatively closer spaced locations to which the rope extents converge from the upper guide means.

7. An exercise device according to claim 6 in which said resistance control means is carried by the frame centrally above and below the longitudinal center of the shaft.

8. An exercise device according to claim 7, in which said resistance control means are essentially rope-passing hooks carried by the frame.
